US00D921015S

(12) **United States Design Patent** (10) Patent No.: **US D921,015 S**
Dedonato et al. (45) Date of Patent: **** Jun. 1, 2021**

(54) **DISPLAY PANEL OR PORTION THEREOF WITH A GRAPHICAL USER INTERFACE**

(71) Applicant: **MAGIC LEAP, INC.**, Plantation, FL (US)

(72) Inventors: **Amy Dedonato**, Plantation, FL (US); **Lorena Pazmino**, Wilton Manors, FL (US); **Gregory Minh Tran**, Miami, FL (US)

(73) Assignee: **Magic Leap, Inc.**, Plantation, FL (US)

(**) Term: **15 Years**

(21) Appl. No.: **29/723,014**

(22) Filed: **Feb. 4, 2020**

CLAIM

The ornamental design for a display panel or portion thereof with a graphical user interface, as shown and described.

DESCRIPTION

FIG. 1 is a front view of a display panel or portion thereof with a graphical user interface showing our new design; and, FIG. 2 is another front view thereof shown in a different broken line environment.

The outermost broken line rectangle illustrates a display panel or portion thereof and forms no part of the claimed design. The remaining broken lines illustrate portions of a graphical user interface or a mixed reality environment and form no part of the claimed design.

1 Claim, 2 Drawing Sheets
